UNITED STATES PATENT OFFICE

SAMUEL J. GREENBERG, OF BROOKLYN, NEW YORK

DESIGN FOR A THERMOMETER CARD

Application filed March 18, 1930. Serial No. 34,952. Term of patent 3½ years.

To all whom it may concern:

Be it known that I, SAMUEL J. GREENBERG, a citizen of the United States, residing at 1800 East 18th Street, Brooklyn, in the County of Kings and State of New York, have invented a new, original, and ornamental Design for Thermometer Cards, of which the following is a specification, reference being had to the accompanying drawing, forming part thereof.

The figure is a front elevation of the thermometer card, showing my new design, the card being substantially flat.

I claim:

The ornamental design for a thermometer card, as shown and described.

SAMUEL J. GREENBERG.
